UNITED STATES PATENT OFFICE.

HENDERSON F. HILL, OF BLOOMFIELD, NEW JERSEY, ASSIGNOR TO THE AMERICAN HARDWARE CORPORATION, OF NEW BRITAIN, CONNECTICUT, A CORPORATION OF CONNECTICUT.

PANIC-BOLT CONSTRUCTION.

1,141,338.

Specification of Letters Patent.

Patented June 1, 1915.

Application filed November 25, 1914. Serial No. 873,849.

To all whom it may concern:

Be it known that I, HENDERSON F. HILL, a citizen of the United States, residing at Bloomfield, in the county of Essex and State 5 of New Jersey, have invented certain new and useful Improvements in Panic-Bolt Construction, of which the following is a full, clear, and exact description.

My invention relates to panic bolt constructions of the type wherein a movable operating member on the interior of the door is moved relatively to the door to retract top and bottom fastening bolts.

It is the object of this invention to combine a device of this type with a separate and assembled lock mechanism of the usual door type, and which is applied to the door intermediate its top and bottom and includes a latch bolt operated from the outside of 15 the door by a knob or other manually controlled device, said latch bolt being connected on the inside of the door to the operating mechanism for the top and bottom bolts aforesaid.

My invention combines these two lock mechanisms so that a three-point latch bolt mechanism is provided of the panic exit door type, wherein all three of the latch bolts are moved to retracted position substantially simultaneously either by the operation of the outside knob or by the usual 25 operation of the inside panic bolt operating member.

Furthermore, my device is so constructed 35 as to permit the use of the inside mechanism without the intermediate or middle lock mechanism, by simply removing a single connecting element between the two.

One embodiment of the invention is described in detail in the following specification, taken in connection with the accompanying drawings forming a part thereof and in which:

Figure 1 is an inside view of a door 45 equipped with a device of the present invention, the door being shown in closed and latched position. Fig. 2 is a view in end elevation of the door in closed and latched position, the parts being shown in section. Fig. 50 3 is a view similar to Fig. 1 but with the latch bolt retracted. Figs. 4-6 show details of the lock mechanism.

Referring to these drawings by numerals, 1 indicates a door of the usual type and 2

the jamb thereof, 3 indicating the door casing at the top and bottom of the door. Secured to the inner face of the door intermediate its top and bottom edges are guide brackets 4 and 5; which serve to guide the upper and lower ends respectively of an inside bar 6. This bar forms an inside operating bar for the top and bottom latch bolts. In the present instance, the lower latch bolt is shown as comprising the lower end of the bar 6, this lower latch bolt being indicated at 7. The upper latch bolt is shown as comprising a hooked head 8 for the upper end of the bar 6, this head 8 latching over the cross bar 10^a of a bracket plate 10 secured to the under face of the door casing, the lower bolt-end 7 engaging a second stop-abutment. One such abutment is shown in the drawings as comprising a socket plate 9 sunk in the floor forming the bottom casing of the door when closed. The specific forms of latches form no part of this invention, and the latch heads 7 and 8 and their connection to the operating bar 6 may be varied as desired, the main requirement being that movement of the bar 6 in one direction serves to move these top and bottom bolts to a position in which the door may be opened and, as will be seen later, also serves to retract an intermediate latch bolt.

The inside bar 6 intermediate its ends is provided with a block 11 having an elongated aperture 12 therethrough in the direction of the door, and providing there-within upper and lower abutments 13. On the inner side face of this block 11, adjacent its rear edge, the rack 14 is provided. This rack may be readily formed thereon by casting or may comprise a separate member, if desired.

Mounted on the inner face of the door in substantial alinement with the guides 4 and 5, and adjacent the inside bar 6, is a plate 15 having an outwardly extending arm 16 adjacent one edge thereof and having also an aperture 17 therein designed to receive the operating spindle of the intermediate latch, as will be seen later. The inside operating means for the top and bottom bolts may comprise any suitable manually controlled means. An ordinary form is shown in the drawings as comprising the usual U-shaped cross bar of a panic bolt mechanism, one end of this cross bar being pivotally

mounted on the arm 16 of the plate 15, the opposite end (not shown) being similarly hinged, as usual. The end of the cross bar 18, which is journaled upon the arm 16, is provided with a finger 19, which extends through the opening 12 of the block 11 and sufficiently far to engage the abutments 13. The bar 18 is so hinged that normally, by gravity, its weight, through the finger 19, presses against the upper abutment 13 of the bar in a direction to move said bar to retract the latch bolts. The weight of this cross bar, however, is not sufficient to accomplish this purpose but merely serves as an aid in the retraction of the latch bolts, reducing the load on the operating parts.

The two-point latch bolt mechanism described may be combined with the usual lock mechanism of a door, to give a three-point latch panic bolt in the following manner: The standard form of door lock, such as a mortise lock, is applied to a door in the usual manner. No special form of lock is necessary, the only requisite being that the lock mechanism, which is separate and assembled relative to the inside panic bolt mechanism heretofore described, includes a latch bolt which will be positioned intermediate the top and bottom of the door and at the side edge thereof in the usual manner of locks, and which will be actuated from the outside of the door by any suitable manually operable means, such as the usual knob; the lock mechanism furthermore requiring a rotatable latch-retracting spindle operatively connected with the outside knob and extending to the inside of the door. In practice, one such spindle is afforded by the inside knob spindle found in the ordinary lock.

In the drawings 20 designates the lock case of a mortise lock of standard construction, 21 the latch bolt thereof and 22 the outside knob by which the latch bolt is retracted from the outside of the door. Assuming that such a mortise lock mechanism is applied to provide a latch bolt intermediate the top and bottom of the door and that the spindle 23 of the inside knob extends through and beyond the inner face thereof; the inside two point latch mechanism heretofore described is coupled thereto by first applying the plate 15 so that the latch-retracting spindle 23 will extend through the opening 17 therein. This will automatically indicate the line of application of the guides 4 and 5 and of the bar 6 and its bolts to the inside face of the door. The inside knob spindle 23 will extend through the aperture 17 in the plate 15. I couple this spindle to the operating bar 6 by means of a pinion 24, which is readily mounted therein and meshes with the rack 14 on the block 11 of the bar 6. Preferably I form the pinion 24 with a

boss 25 which will journal in the opening 17 of the plate 15, the socket for the spindle 23 extending through the boss and pinion so that the latter is readily coupled to the spindle and is also provided with a bearing in the plate.

It will be seen from the foregoing that movement of the cross bar 18 toward the door will bring the finger 19 upwardly to lift the bar 6 to a position where the top and bottom latch bolts are disengaged from the abutments or, in other words, "retracted." At the same time, as the block 11 is moved upwardly, the rack 14 thereof will rotate the pinion 24 and spindle 23, retracting the middle latch bolt 21 so that the top and bottom latch bolts and intermediate latch bolt will be retracted simultaneously, thereby permitting the door to be opened from the inside.

The operation of the mechanism from the outside is as follows: By turning the outside knob 22 in the usual latch-retracting direction, the middle latch 21 is of course retracted. As the inside knob spindle is operatively connected with the outside knob spindle and is rotated when the outside knob is turned, the pinion 24 will also be turned when the outside knob is turned and this rotation of the pinion will operate the rack 14 and bar 6 upwardly to move the top and bottom latch bolts to retracted position substantially simultaneously with the middle latch bolt 21. As the weight of the cross bar, by gravity, operates against the bar 6 in latch-retracting direction, it will be obvious that the load strain upon the outside knob is not made unduly heavy.

It will be noted that by operatively connecting the inside operating means (the cross bar) with the inside bar 6, independently of the latch-retracting spindle connection thereto, the parts on the inside of the door may be used as the ordinary two-point panic bolt latch, the block 11 of course having a rack 14 thereon, the mortise lock mechanism and the coupling pinion 24 being dispensed with. An essential element of the operating connection between the mortise lock mechanism and the upper and lower bolts (pinion 24) is therefore removable without affecting the connection between the upper and lower bolts and the operating bar. It will be seen therefore that I have reduced the operating mechanism to comparatively few parts, of simple construction and easy of assembling in co-operative relation.

While I have herein illustrated a particular embodiment of my invention, it will be understood that the same is susceptible of variation both in structure and in relative arrangement of parts within the spirit of the invention and the scope of the appended claims.

What I claim therefore and desire to secure by Letters Patent is:

1. In combination, a door, top and bottom latch bolts on the inner face thereof, a bolt-operating bar upon said inner face in operative retracting connection with said bolts, a separate and assembled lock mechanism carried by the door including an intermediate latch bolt at the side edge of the door 10 with a manually controlled operating member therefor on the outside of the door and with a rotatable latch-retracting spindle in operative connection with said outside operating member, said latch spindle extending to the inside of the door with operative connections between said spindle and said inside bolt-operating bar, a manually controlled inside operating member coöperating with said inside bar independently of said 15 latch spindle connections, said inside and outside operating members being arranged to severally effect retraction of said top, intermediate and bottom latch bolts substantially simultaneously, a connecting element 20 of said operative connections between said spindle and inside bar, being removable without affecting the operative connection between said top and bottom latch bolts and said manually controlled inside operating member.
2. In combination, a door, top and bottom latch bolts on the inner face thereof, a bolt-operating bar upon said inner face in operative retracting connection with said 25 bolts, said inside bar having a rack, a separate and assembled lock mechanism carried by the door including an intermediate latch bolt at the side edge of the door with a manually controlled operating member therefor 30 on the outside of the door and with a rotatable latch-retracting spindle in operative connection with said outside operating member, said latch spindle extending to the inside of the door and having a pinion thereon meshing with said inside bolt-operating 35 bar rack, a manually controlled inside operating member coöperating with said inside bar independently of said latch spindle pinion and rack connections, said inside and outside operating members being arranged 40 to severally effect retraction of said top, intermediate and bottom latch bolts substantially simultaneously, a connecting element 45 of said operative connections between said spindle and inside bar, being removable without affecting the operative connection between said top and bottom latch bolts and said manually controlled inside operating member.
3. In combination, a door, top and bottom latch bolts on the inner face thereof, a bolt-operating bar upon said inner face in operative retracting connection with said bolts, said inside bar having a rack and an abutment 50 separate therefrom, a separate and as- 55 sembled lock mechanism carried by the door including an intermediate latch bolt at the side edge of the door with a manually controlled operating member therefor on the outside of the door and with a rotatable latch-retracting spindle in operative connection with said outside operating member, said latch spindle extending to the inside of the door, a plate supported 60 on the inside of the door adjacent said inside bar, said plate having an aperture therein to receive said latch spindle, 65 operative connections between said latch spindle and said inside bar, and an inside 70 manually controlled operating member operatively connected with said inside bar independently of said latch spindle connections, said inside and outside operating members being arranged to severally effect retraction of said top, intermediate and bottom latch bolts substantially simultaneously.
4. In combination, a door, top and bottom latch bolts on the inner face thereof, a bolt-operating bar guided on said inner face and in operative retracting connection with said bolts, a separate and assembled lock mechanism carried by the door including an intermediate latch bolt at the side edge of the door with a manually controlled operating member therefor on the outside of the door and with a rotatable latch-retracting spindle in operative connection with said outside operating member, said latch spindle extending to the inside of the door, a plate supported 75 on the inside of the door adjacent said inside bar, said plate having an aperture therein to receive said latch spindle, 80 operative connections between said latch spindle and said inside bar, and an inside 85 manually controlled operating member operatively connected with said inside bar independently of said latch spindle connections, said inside and outside operating members being arranged to severally effect retraction of said top, intermediate and bottom latch bolts substantially simultaneously.
5. In combination, a door, top and bottom latch bolts on the inner face thereof, a bolt-operating bar guided on said inner face and in operative retracting connection with said bolts, said bar having a rack thereon and an abutment separate therefrom, a separate and assembled lock mechanism carried by the door including an intermediate latch bolt at the side edge of the door, with a manually controlled operating member therefor on the outside of the door and with a rotatable latch-retracting spindle in operative connection with said outside operating member, said latch spindle extending to the inside of the door, a plate supported 90 on the inside of the door adjacent said inside bar, said plate having an aperture therein to receive said latch spindle, 95 operative connections between said latch spindle and said inside bar, and an inside 100 manually controlled operating member operatively connected with said inside bar independently of said latch spindle connections, said inside and outside operating members being arranged to severally effect retraction of said top, intermediate and bottom latch bolts substantially simultaneously.

the inside of the door adjacent said inside bar, said plate having an aperture therein to receive said latch spindle, a pinion carried by said spindle and meshing with the 5 rack on said inside bar, and a manually controlled operating member carried by said plate and arranged to engage said inside bar abutment, said inside and outside operating members being arranged to severally effect 10 retraction of said top, intermediate and bottom latch bolts, substantially simultaneously.

6. In combination, a door, top and bottom latch bolts on the inner face thereof, a bolt-operating bar upon said inner face in 15 operative retracting connection with said bolts, a separate and assembled lock mechanism carried by the door including an intermediate latch bolt at the side edge of the door with a manually controlled operating member therefor on the outside of the door and with a rotatable latch-retracting spindle in operative connection with said outside operating member, said latch spindle extending to the inside of the door with 20 operative connections between said spindle and said inside operating bar, a manually controlled inside operating member coöperating with said inside bar independently 25 of said latch spindle connections, said inside and outside operating members being arranged to severally effect retraction of 30 said top, intermediate and bottom latch bolts substantially simultaneously, the weight of

said inside operating member operating by gravity against said inside bar in the direction of latch-retracting movement thereof. 35

7. As an article of manufacture, a panic bolt mechanism for application to one face of a door comprising top and bottom latch bolts, a bar for operative retracting connection with said bolts, said bar having a 40 rack thereon, a manually controlled operating member, said member being arranged for operative connection with said bar independently of said rack, with means whereby 45 said member may be supported on said door face for movement in latch retracting direction.

8. As an article of manufacture, a panic bolt mechanism for application to one face 50 of a door comprising top and bottom bolts, a bar for operative retracting connection with said bolts, said bar having a rack thereon, and having an operating abutment separate from said rack, a plate arranged to be 55 secured to said door face adjacent said bar, a manually controlled operating member arranged to be supported by said plate and to engage said abutment to move said bar in a direction to retract said bolts, said plate 60 having an opening therein adjacent said bar rack.

HENDERSON F. HILL.
